UNITED STATES PATENT OFFICE

HENRY TSCHERNING, OF FREEPORT, ILLINOIS, ASSIGNOR TO ARCADE MANUFACTURING COMPANY, OF FREEPORT, ILLINOIS, A CORPORATION OF ILLINOIS

MOP HEAD

Application filed October 27, 1927. Serial No. 229,047.

My improvement relates to mop heads of the type comprising a jaw member on the head forming one of the clamps between which the mop is secured, the other jaw being in the form of a bail adapted to be moved into and out of clamping position, and an abutment on the head against which the head of a brush may be clamped by the bail when it is desired that the mop device have a brush applied thereto.

My object is to provide a novel, simple and inexpensive construction of mop head of the type referred to.

Referring to the accompanying drawing: Figure 1 is a view in elevation of a mop device having a head constructed in accordance with my invention. Figure 2 is a plan view of the head of Fig. 1. Figure 3 is a section taken at the irregular line 3-3 on Fig. 1 and viewed in the direction of the arrow. Figure 4 is a broken section taken at the line 4-4 on Fig. 1 and viewed in the direction of the arrows; and Figure 5, a section taken at the line 5 of Fig. 3 and viewed in the direction of the arrow.

The mop head shown comprises a member 5 of sheet metal deformed intermediate its ends to provide a substantially semi-cylindrical portion 6, the upper edge of the member 5 being formed with tongues 7. Extending along the upper edge of the member 5 is a trough member 8 containing a series of slots 9 through which the tongues 7 project, the upper ends of the tongues being deflected in opposite directions to secure the member 8 to the member 5, the trough 8 containing notches 10 in its ends and constituting one of the members of a clamp between which the mop (not shown) is secured.

The other member of the clamp referred to is represented at 11 and is in the form of a bail the ends of which are pivotally connected with a lever 12, the forward end of which is pivotally connected with one end of a coil spring 13 surrounding the mop stick represented at 14 and abutting at its other end against the mop head, the parts just referred to being provided to yieldingly force the clamp member 11, at its cross-bar section 15, into clamping relation with the trough

member 8 for releasably holding the mop in place upon swinging lever 12 to the position shown, the bar portion 15 of the clamp member 11 extending along one side of the trough 8, and the spring 13 being shown as provided with a deflected portion 13a where it extends through the lever 12 to prevent turning of the spring.

The head also comprises a member 16 also preferably of sheet metal and of general U-shape, the cross-bar portion of which, and represented at 17, being deformed between its ends to provide a substantially semi-circular portion 18. The member 16 is positioned flatwise against a face of the member 5 at the side thereof adjacent to which the cross-bar of the clamp 11 extends and is secured to the member 5 by rivets represented at 19, the semi-cylindrical portion 6 and 18 of the plates 5 and 16, respectively, extending in a position in which they, together, form a socket into which the outer end of the mop stick 14 extends and at which socket portion the mop head is securely held to the mop stick, as for example by a nail 20 passing through an opening in a wall of this socket and into the mop stick.

The laterally outwardly projecting leg-portions of the member 16 are represented at 21, these portions being preferably of the general triangular shape shown with their upper edge, represented at 22, inclining downwardly and outwardly away from the trough member 8 and terminating at their lower ends in shoulder portions 23, the parts just described being so constructed and arranged that the mop device may be equipped with a brush (not shown) if desired by positioning the brush head upon the surfaces 22 to engage along one edge thereof with the shoulder 23, and engaging the opposite edge of the brush head with the cross-bar of the clamping bail 11.

The device thus provided is adapted to be used either as a mop-holder or a brush-holder, as desired, and by constructing the device as described is not only of simple and inexpensive construction but may be readily manipulated to serve the double purpose stated.

While I have illustrated and described a particular construction embodying my invention,

tion I do not wish to be understood as intending to limit it thereto as the same may be variously modified and altered without departing from the spirit of my invention as defined in the appended claims.

5 What I claim as new, and desire to secure by Letters Patent, is:

1. A combined mop and brush-holding head comprising first, second and third members, said first and second members having abutting flat portions deflected outwardly medially to provide a stick-receiving socket, tongues on one of the latter members, the third member being a trough and disposed across 15 and in contact with each of said first and second members at an edge of the abutting portions, said trough having slots through which said tongues pass to secure the trough in place, a bail coacting with the trough to secure a mop thereto, the second member having shoulders, and said bail having a portion co- 20 acting with said shoulders to hold a brush in operative position.

2. A combined mop and brush-holding 25 heading head having a pair of flat abutting members collectively providing a stick-receiving socket, a trough member disposed along an abutting edge of the first mentioned members and secured to one of them in rigid 30 relation therewith, one of said members having outwardly extending portions provided with shoulders, a bail having portions extending across the trough, and a portion be- 35 yond the trough connecting the first mentioned portions and coacting with the shoulders to clamp a brush in operative position.

HENRY TSCHERNING.
